UNITED STATES PATENT OFFICE.

JOHN H. SHAW, OF NEW HAVEN, CONNECTICUT, ASSIGNOR TO SARGENT & COMPANY, OF NEW HAVEN, CONNECTICUT, A CORPORATION OF CONNECTICUT.

LOCK.

Application filed December 22, 1919. Serial No. 346,481.

To all whom it may concern:

Be it known that I, JOHN H. SHAW, a citizen of the United States, residing in New Haven, in the county of New Haven and 5 State of Connecticut, have invented certain new and useful Improvements in Locks, of which the following is a full, clear, and exact description.

This invention relates to locking mechanism, and more particularly to locking mechanism for the type of door which is provided with an escutcheon plate having a mail receiving passage formed therethrough.

15 Heretofore door locks have been provided with relatively large escutcheon plates in which mail receiving slots are formed, so that the escutcheon plate in addition to its usual function serves also as a guard plate 20 for the mail slot in the door. This arrangement is open to the objection that after the door has been locked, it is comparatively easy to open the same without a key by inserting an instrument through the mail slot 25 formed in the escutcheon plate to operate the knob or other lock mechanism upon the inside of the door.

The primary object of my invention, therefore, is to prevent the type of door having 30 a mail slot formed through its escutcheon plate from being successfully attacked in the manner above indicated.

A more specific object of my invention is to provide the mail slot of the escutcheon 35 plate with a protecting flap and to provide means operated by this flap for preventing the opening of the door while this flap is open.

To these and other ends the invention consists in the novel features and combinations 40 of parts to be hereinafter described and claimed.

In the accompanying drawings:

Fig. 1 is a fragmentary side view of a 45 door having my invention applied thereto.

Fig. 2 is a front edge view of Fig. 1.

Fig. 3 is a vertical sectional view taken 50 on the line 3—3 of Fig. 2 looking in the direction of the arrows and showing the flap for the mail slot open.

Fig. 4 is a view similar to Fig. 3, but showing the mail flap closed; and

Fig. 5 is a sectional view taken substantially 55 on the line 5—5 of Fig. 3 looking in the direction of the arrows.

In the drawings, I have designated by the numeral 10 the portion of a door having my invention applied thereto. Within the front edge of this door is mounted in the usual manner a mortise lock designated in its entirety by the numeral 11, and this mortise lock is provided with an outside escutcheon plate 12 and an inside escutcheon plate 13 secured to the door 10 by the screws 14. These escutcheon plates are made rather large and extend downward below the mortise lock 11 a sufficient distance to have a mail receiving slot formed through the same below the mortise lock, in alignment with a corresponding opening 10' formed through the door. In 70 the embodiment of my invention illustrated, I have shown the outside escutcheon plate 12, as provided with a hinged flap 15 swingingly mounted upon the inner face of this escutcheon plate and positioned to close the 75 mail slot formed in the same. The escutcheon plate 12 is preferably provided with the inwardly projecting lugs 16 positioned to have the lugs 17 upon the flap 15 pivotally secured thereto by the pivot pin 18, and the 80 flap is normally held in its closed position, as shown in Figs. 1 and 2 by a coiled spring 19.

In order to prevent the bolt controlling mechanism upon the inside of the door from 85 being operated to unlock the door by inserting an instrument through the letter slot, I have provided the mortise lock 11 with the mechanism controlled by the flap 15, which I will now describe. The mortise lock 11 90 may be provided with the usual or any preferred mechanism, such as for example the usual spring operated latch bolt 20, the dog controlling plunger 21, which is provided to operate the latch dogging lever 22, and the latch bolt 20 is shown as provided with the usual retracting yoke 23 operated by the knob operated hub 24 and in order that the latch bolt may be provided with key controlled means for retracting the same, I have 95 shown the usual relatively long pivoted lever 25, which is operated by the rollback 26 of a cylinder lock 27. In addition to the mechanism, just described, within the mortise lock 11, I have provided therein a separate and independent sliding bolt 28, which is operated by a vertically sliding member 29, a pivoted bell crank lever 30 preferably being provided to operatively connect the member 29 to the sliding bolt 28. The bell 100 105 110

crank lever is pivoted upon the fixed post 31 and one arm of this bell crank is shown as provided with a pin 32 operatively received in the elongated opening 33 formed 5 in the bolt 28 adjacent the rear end of the same. The other arm of the bell crank may be similarly connected to the vertically sliding member 29, and the bolt 28 is normally held in its retracted position by a coiled 10 spring 34 positioned about the post 31 and having one end reacting against an arm of the bell crank lever to rock the same. The vertically sliding member 29 is provided with a lower end projecting through the bottom 15 of the mortise lock casing and this lower end is preferably provided with a horizontally extending foot 35. In order to provide means for raising the member 29 by the opening of the flap 15, I have provided the 20 rocking member 36, which is pivotally secured to the inner face of the escutcheon plate 12, this plate being provided with the inwardly projecting lugs 37, to which the member 36 is pivotally secured by a pivot 25 pin 38. This member 36 is provided with a cam-like portion 36' adapted to operatively engage the foot 35 to lift the sliding member 29 when the rocking member 36 is raised. The flap controlled means just described is 30 so constructed that so long as the flap is retained in its closed position by its spring 19, as shown in Figs. 1, 2 and 4, the pivoted member 36 will be permitted to swing downward to the position clearly shown in dotted 35 lines in Fig. 2 and this in turn will permit the sliding member 29 to move downward to the position shown in Fig. 4, as the bolt 28 is retracted by its operating spring 34. Since the rocking member 36 normally lies 40 below the upper edge of the hinged flap 15, it will be seen that whenever this flap is forced open, the upper edge of the same cooperates with the pivoted member 36 to swing the same upward to the position 45 shown in Fig. 5, whereupon the cam member 36' which operatively engages the foot 35 forces the sliding member 29 upward, and this member in turn moves the sliding bolt 28 to its projected position.

50 From the foregoing description, when read in connection with the drawings, it will be seen that whenever the flap 15 is opened, the auxiliary bolt 28 will be moved to its extended position by the operating slide 29 and pivoted member 36, so that if an instrument is inserted through the letter slot by an unauthorized person attempting to open the door in this manner, even if he succeeds in retracting the latch bolt 20, he will not 55 be able to open the door, since the auxiliary bolt 28 will remain protracted so long as the letter flap is held open. If for any reason the coiled spring 34 should fail to retract its bolt 28 after the flap 15 has been closed,

60 65 I have provided a projection 39 upon the

upper end of the slide 29 positioned to be operatively engaged by the roll-back 26, so that if necessary, the auxiliary bolt 28 may be retracted by bringing the roll-back 26 into operative engagement with the upper 70 end of the sliding member 29, as shown in Fig. 3.

It will be apparent that various minor changes may be made in the device herein disclosed without departing from the scope 75 of my invention, as defined in the annexed claims.

What I claim is:

1. Locking mechanism comprising, an escutcheon plate having a passage therethrough, a protecting flap for closing said passage, a normally retracted bolt, and means operated by said flap to project said bolt from the lock by the opening of said flap. 80

2. Locking mechanism comprising, an escutcheon plate having a passage therethrough, a protecting flap normally closing said passage, a bolt, and means operable by said flap to project said bolt from the lock 90 by the opening of said flap.

3. Locking mechanism comprising, an escutcheon plate having a mail receiving passage therethrough, a protecting flap normally closing said passage, a bolt, and means 95 operable by said flap to project said bolt from the lock by the opening of said flap.

4. Locking mechanism comprising, an escutcheon plate having a passage therethrough, a protecting flap therefor, a latch bolt, and a second bolt provided with means to project the same from the lock by the 100 opening of said flap.

5. Locking mechanism comprising, an escutcheon plate having a passage therethrough, a protecting flap therefor, a latch bolt, and a second bolt provided with means to project the same by the opening of said flap, said second bolt provided with key operable means for retracting the same. 105

6. In combination with a door, a mortise lock mounted therein, an escutcheon plate for said lock having a mail slot formed therethrough, a protecting flap for closing said mail slot, and a bolt within said lock 115 provided with means for projecting the same from the lock by opening said flap.

7. In combination with a door, a mortise lock mounted therein, an escutcheon plate for said lock having a mail slot therethrough, a protecting flap for said slot, and locking means normally within said lock but projectable therefrom by said flap to prevent the opening of said door while said flap is open. 120

8. In combination with a door, an escutcheon plate having a mail slot therethrough, a protecting flap for said slot, and means operable by said flap for locking said door. 125

9. Locking mechanism for a door having a passage therethrough comprising a latch 130

bolt, a closure member for said passage, and means independent of said bolt and controlled by said member for locking the door when said passage is open.

5 10. A lock having an escutcheon plate with an opening therethrough, a hinged closure member for said opening, a latch bolt, and locking means projectable from said door by the movement of said closure member.

10 11. Locking mechanism for a door having a passage therethrough comprising a closure member for said passage and a lock having a locking member projectable into locking position by the movement of said closure member.

15 12. In combination a door having an opening therein through which articles may be inserted, and a lock having a bolt projected into locking position by the insertion of an article into said opening.

20 13. In combination with a door having a passage therethrough and a projecting flap

for said passage, a cam member hinged above said flap and a bolt projected by said cam member to prevent the opening of said door when said flap is open.

14. In combination, a door having a passage therethrough, a protecting closure member normally closing said passage, a lock having a projectable bolt, means operable by the spring of the closure member to project the bolt from the lock, and key operated means to retract the bolt to unlock the door.

35 15. In combination, a door having an opening therethrough, a closure member normally closing the opening, a lock having a bolt projectable into locking position, means connecting said member to the bolt whereby the bolt is projected when the member is opened, and a key operated member acting upon said means operable to retract the bolt.

In witness whereof, I have hereunto set my hand on the 18th day of December, 1919.

JOHN H. SHAW.
